SEGMENTAL GRINDING WHEEL

Application filed December 15, 1930. Serial No. 502,374.

This invention relates to segmental grinding wheels and especially to a grinding wheel composed of a multiplicity of bonded abrasive segments firmly secured together to form a unitary grinding annulus capable of being handled and transported independently of any rotatable support upon which it may later be mounted to rotate therewith and perform a grinding operation.

It has been found highly impractical to manufacture large monolithic abrasive wheels composed of abrasive grains bonded together by a vitrified ceramic material sufficiently strong to withstand the high rate of rotation necessary for many of the present day grinding operations. Furthermore, the firing operation for these large wheels may often result in their breakage, since it is practically impossible to heat a large abrasive mass with uniformity and thereby maintain an even expansion throughout the entire wheel structure. As a consequence, it has been found advantageous to construct many of the large size abrasive wheels from a multiplicity of abrasive segments which are individually clamped in position upon the peripheral surface of a large cast iron drum and thereafter cemented in place, thus forming an integral wheel structure capable of a high speed rotation without any of the inherent structural weaknesses of the previous monolithic wheel constructions. Owing to their great size and massive weight, these cast iron supporting drums have been expensive to manufacture and ship. In assembling wheels of this type, there is a loss of time which involves further expense since each individual segment must be accurately fitted and firmly clamped in its respective position upon the peripheral surface of the supporting drum. Furthermore, a massive cast iron supporting drum of this type may add a weight of several tons to the abrasive annulus which necessitates a large supporting shaft and immense bearings therefor.

Whenever one of these massive wheels breaks down or wears out, it is necessary to return the entire wheel and supporting drum to the factory for repair or replacement of new segments upon the old drum. Obviously,

such a repair places the grinding machine in an inoperative condition for a considerable time as well as involving the expense of dismantling the machine, forcing the heavy drum from its shaft, shipping it and the abrasive annulus affixed thereto to the factory for repair and then back to the grinding machine for reinstallation upon its shaft. Mounting a massive grinding wheel of this type usually requires skilled labor and special equipment since such a grinding wheel may often weigh several tons and require careful balancing upon its supporting shaft. The wheel user's only alternative to save this expensive delay has been to keep a spare grinding wheel on hand, which often involved an expense of several thousand dollars.

Therefore, the principal object of my invention is to provide a segmental grinding wheel having a multiplicity of abrasive segments intimately secured together and forming a substantially unitary abrasive annulus which may be transported independently of and removably mounted upon any rotatable support of a standard size.

A further object is to provide a segmental grinding wheel in which the abrasive segments are interlocked with a series of supporting members and form an integral wheel structure rigidly mounted upon a rimless rotatable support and thereby avoid the expense and time involved in fitting the segments to the peripheral surface of a supporting drum.

In accordance with my invention, I have provided a unitary segmental abrasive wheel composed of a plurality of separately manufactured abrasive segments arranged to form an annulus and interlocked with a series of peripherally spaced girders rigidly secured thereto by a cementitious medium flowed into the crevices between the adjacent segment faces and between the girders and the adjacent segment faces, thereby forming an integral abrasive annulus capable of use as a grinding wheel. This abrasive annulus may be transported as a unit independently of any rotatable support upon which it is ultimately mounted to rotate therewith and perform a

grinding operation. Each abrasive annulus is made to conform with a standard pattern and is provided with parts which are arranged to fit a standardized central rotatable support whereby a worn-out abrasive annulus may be quickly and easily replaced by a new abrasive annulus without necessitating that the rotatable support or hub even be removed from its shaft. When mounted upon a rotatable member the girders form not only an interlock to hold the segments together but also a rimless support which carries the radial pressure on the wheel segments.

If desired, the abrasive annulus may be constructed to be integral with the central rotatable support, in which case the interlocking girders are rigidly and permanently secured to rotatable supporting members, and as in the former case they provide a rimless support as distinguished from the supporting drum used heretofore in this art. The abrasive segments are laterally slid into position between adjacent girders and interlocked therewith by means of any suitable cementitious filler inserted into the crevices between the adjacent parts, thus forming an integral and rigid wheel structure. In this construction, when the wheel is worn out the entire structure must be discarded or shipped back to the factory for removal of the old abrasive segments and replacement of new ones in their stead.

I have illustrated in the accompanying drawings embodiments of both types of my invention, wherein Figs. 1 to 6 show segmental grinding wheel structures having an abrasive annulus which may be transported independently of any rotatable support and Figs. 7 to 10 show a segmental grinding wheel structure wherein the abrasive body and its rotatable support comprise a unitary structure.

Referring to Figs. 1 to 6, Fig. 1 is a perspective view of an assembled grinding annulus having a portion thereof broken away to more clearly illustrate the method of interlocking the adjacent abrasive segments and girders;

Fig. 2 is a fragmentary view showing a girder member embedded within the cement and locking two adjacent segments together;

Fig. 3 is a sectional view showing a method for removably mounting a unitary abrasive annulus upon a supporting hub for rotation therewith;

Fig. 4 is a fragmentary view which shows a modified form of an abrasive annulus adapted to be removably secured to a supporting hub;

Fig. 5 is a sectional view taken substantially along the line 5—5 of Fig. 4; and

Fig. 6 is a sectional view taken along the line 6—6 of Fig. 4.

Referring to Figs. 7 to 10, Fig. 7 is a perspective view of an assembled segmental grinding wheel having a portion broken away

to more clearly illustrate the unitary wheel structure;

Fig. 8 is a perspective view of the girder which fastens the side plates together and interlocks with adjacent wheel segments to form a unitary wheel structure;

Fig. 9 is a fragmentary view taken in elevation showing the wedge shaped abrasive segments and their relative positions in the finished wheel structure; and

Fig. 10 is a fragmentary view in central section along the irregular line 10—10 of Fig. 9.

As illustrated in Figs. 1, 2 and 3 of the drawings, the preferred form of my invention comprises a substantially unitary abrasive annulus 10 which is transportable independently of a rotatable support upon which it may be removably mounted. This abrasive annulus 10 consists of a plurality of similar, individually fashioned, wedge-shaped, arcuate segments 11 composed of abrasive grains bonded together by any suitable vitrified ceramic materials, and these segments are positioned with adjacent radial faces 13 spaced apart so that their external curved surfaces together form a cylindrical grinding face. The end faces 14 of the segments 11 are cuneated or dovetailed in form, and each radial face 13 of the segment is provided with reentrant surfaces 15 forming a groove which cooperates with the opposed groove on the adjacent segment to carry a girder member 18. These girder members 18 are preferably arranged substantially parallel to the axis of the abrasive annulus and are positioned radially of the grinding annulus so that a girder may fit between each two adjacent segments and interlock therewith.

The girder members 18 are single piece metal bodies comprising a flange or base 20 from which rises a radial web 21 terminating in an enlarged head 22 which is shaped to fit within both of the reentrant portions of the two adjacent segments and interlock therewith when the abrasive annulus is assembled. The top of the base 20 serves to form two supporting shoulders 23 one upon each side of the web 21 which locate and radially support the abrasive segments in correct position for rotation. The head 22 and the shoulder 23 interlock with the dovetailed portion of the segment and support it against radial stresses due to centrifugal and centripetal forces arising during transportation or use during a grinding operation.

To securely bind the abrasive segments and girders together into an integral annulus which is readily transportable as a unit independently of any rotatable support, I have secured the various members of this structure together by any suitable cementitious medium 24, examples of which are a molten metal, such as lead or babbitt, and a

molten mixture of sulfur and ground coke which is commonly known under the trademark "Lavasul". As clearly shown in Fig. 2, this cementitious medium 24 is cast in position after the annulus has been assembled, so that it completely fills the interstices between the two radial faces 13 of each pair of adjacent segments and also fills the crevices between the segments and each girder 18, thus embedding it therein so that each segment is firmly and permanently seated in correct position thereon and interlocked therewith. When thus made, the abrasive annulus may be rigidly mounted on a rimless supporting center, and removed therefrom as desired.

To removably fasten my grinding annulus 10 to a rotatable support or hub for rotation therewith, I provide means for securing the girders to a central rotatable support, which may be so arranged that the annulus may be either removable therefrom or permanently secured thereto. In the form shown in Figs. 1 to 6, the annulus is made removable, and one suitable means for so doing may comprise holes 25 within the end faces of each girder base 20 which in the present instance are tapped to receive threaded studs 27 passing through and secured by nuts 28 to two disk-like plates 29 removably mounted upon a hub 30 by means of a series of cap screws 31 threaded into flanges 32 upon either end of said hub. To prevent any undue strain or excess shearing action upon the studs 27 and cap screws 31, I have provided the central bore of each plate 29 of such size that it may fit snugly over the hub 30 and I have also provided a recess and flanged portion 33 adjacent to the periphery of each plate 29, so shaped that it will mate with a similar recess and flange portion 34 upon the end face of the base 20 of each girder member 18. Thus all of the strains due to centrifugal and centripetal forces are transmitted from the abrasive annulus 10 through the girder members 18 which are rigidly secured to the plates 29 and thence directly to the hub 30 without creating any dangerous shearing action upon the studs and cap screws which hold the various parts in proper location relative to one another.

To assemble my abrasive annulus and form an integral grinding structure which may be removably mounted upon any standard size supporting plates and hub, I provide a pair of master plates which are identical with the standard size plates 29 upon which the girder members are finally removably mounted. The girders 18 are rigidly fastened in correct location by means of studs 27 and nuts 28, thus supporting the girders in exact position preparatory to assembling the abrasive segments therewith. The abrasive segments are individually and laterally slid into position between each pair of girder members so that the dovetailed portion of each segment may

interlock between the opposed heads of adjacent girders. During assembly the segments are circumferentially spaced so that they do not engage one another or the girders, and the interstices between the adjacent radial faces 13 and between the girders and abrasive faces adjacent thereto are filled by casting the cementitious medium 24 therebetween. In this way the segments and girders are permanently secured in their correct relative positions and thereby form an integral abrasive annulus having a series of girder members embedded therein. When the cementitious medium has set, the nuts 28 may be removed and the abrasive annulus and girders removed from the master plates as an integral structure and shipped as a unit to its destination where it may be quickly and easily assembled upon any standard size plates and hub.

I have shown in Figs. 4, 5 and 6 a modified form of my segmental abrasive annulus which may be transportable as an independent unit and removably secured upon any standard size of rotatable support therefor to perform a grinding operation. My annulus is composed of a plurality of radially spaced abrasive segments 40 having opposed radial faces 41 and cuneated or dovetailed portions therebetween which are interlocked with spaced girders 42 radially positioned between each pair of adjacent segments and further secured in correct position by a suitable cementitious filler 44 of the type heretofore described which is cast in position so that it completely fills the interstices between the faces 41 and between the segments and girders. Each girder 42 may comprise a single piece metal body having a web 43 terminating in an enlarged rounded head 45 which has a hole 46 running longitudinally therethrough and within which a stud 47 may be slidably mounted to secure the girder and segments interlocked therewith to a rotatable support.

The end faces of the girders are so formed that each girder is dovetail shaped in longitudinal cross section and is rigidly but removably fastened between two supporting disks 48 by means of nuts 49 screwed upon both ends of studs 47 as clearly illustrated in Fig. 5. The disks 48 are further provided with recessed and flanged surfaces adjacent their peripheries which mate positively with and engage the dovetailed form of each girder, thus preventing any shearing action upon the clamping studs 47 due to radial forces exerted upon the wheel during rotation. Each abrasive segment 40 is further provided with a dovetail portion in cross section of similar shape to that of the girder members but of slightly smaller size so that the disks may firmly clamp against each girder member but will prevent the individual segments from flying from the wheel during its use in case of breakage as shown in Fig. 6. The side

faces of the dovetailed portions upon the segments and girders are cut below the side faces of the segments so that none of the supporting parts will extend beyond the side faces of 5 the wheel should it be desired to use it for a plunge cut grinding operation.

To assemble my abrasive annulus of the modified construction as shown in Figs. 4, 5 and 6 and form an integral grinding structure 10 which may be removably secured upon any standard size supporting plates and hub, I have provided two master disks which are identical with the standard size disks 48 upon which the girder members 42 and segments 15 40 are finally removably mounted. The segments 40 and girders 42 are mounted in spaced relation and clamped in position by studs 47 and nuts 49. During assembly, the segments are circumferentially spaced so that they do 20 not engage each other or the girders, and the spaces between the girders and the adjacent segment faces and between the adjacent radial faces are filled by casting the cementitious medium 44 therebetween. Thus each segment and girder is positively secured in correct relative position, and when assembled, they form an abrasive annulus having a series 25 of girder members embedded therein. When the cementitious filler has set, the nuts 49 may be removed, studs 47 withdrawn and the abrasive segments and girders removed from the master plates as an integral structure which may be transported as an independent unit to its point of use when it may be quickly 30 assembled upon any standard size supporting plates and hub.

As illustrated in Figs. 7, 8, 9 and 10 of the drawings, I have disclosed a further modification of my invention providing an abrasive wheel structure wherein an annulus of 35 individually fastened abrasive segments is permanently secured to a light, rigid, rimless support, thereby forming an integral grinding wheel construction which is much lighter and stronger than any monolithic wheel of 40 comparable size. My abrasive wheel comprises a plurality of abrasive segments 50 arranged the same as in the modifications above described, which are positioned with their 45 radial side faces 51 spaced apart so that the outer curved surfaces of the segments together form a cylindrical face. The end portions 52 of each segment are dovetailed in form and having inner radial faces 51 and 50 reentrant surfaces 53 so arranged that during 55 assembly the individual segments may be laterally slid into position in a direction parallel to the axis of rotation between the girders 55.

60 In order to avoid use of a heavy and expensive cast iron drum or other wheel structure which provides a cylindrical rim or peripheral surface upon which the abrasive segments may be secured, I similarly construct the wheel mount of two plates or disks 56

which are spaced at their peripheries to provide a rimless wheel support; and these are interconnected near their outer faces by the series of girders 55. The girders 55 are each provided with enlarged interlocking heads 70 57 formed at the top of webs 58 arranged radially of the wheel. The girders 55, as illustrated in Fig. 8, may be made of a single piece of metal provided with two depending flanges 59 at either end and at right angles 75 to the web 58 and parallel with the supporting plates 56 to which they are permanently fastened by rivets 62. These depending flanges 59 are connected and strengthened by a central web 63 which is a continuation of 80 web 58. Each girder is further provided with two flanges forming shoulders 64 adjoining the opposite sides of webs 58 which are parallel to the heads 57 and serve to support the abrasive segments thereon. The 85 webs 58 project beyond and overhang the flanges 59 (see Figs. 8 and 10) so that the disks 56 may be properly positioned with their peripheries in engagement with the under surfaces of these webs to better strengthen 90 the abrasive wheel during grinding. Thus the disks are maintained in rigid spaced relationship by the same members which serve to support the abrasive segments and lock them in position. 95

The disks 56 may be mounted in spaced relationship directly upon a driving spindle, but I prefer to support them upon a hub 66. To this accomplishment, the disks 56 are provided with central holes of such size that 100 they fit snugly over the end of the hub 66. The hub portion extending between the disks 56 is provided with radiating arms 67 to which the disks are permanently secured by rivets 69 passing through both disks and the 105 respective arms upon said hub.

In assembling this wheel the hub 66, the plates 56 and the girders 55 are first fastened together permanently, after which the segments are slid laterally into position between their respective girders with which they interlock. The interstices between adjacent radial faces 61 of the segments and between the girders and the segment faces adjacent thereto are filled with a suitable cementitious medium 69, such as described above. As soon as the cementitious medium has hardened and set, the abrasive wheel is ready for shipment and use. 110

This case is a continuation in part of my 120 prior application, Serial No. 257,244 filed February 27, 1928 and allowed September 19, 1930.

Having thus described my invention, what I claim as new and desire to secure by Letters 125 Patent is:

1. A grinding wheel comprising a multiplicity of abrasive segments, a series of girder members each of which is interlocked with two adjacent segments, a cementitious 130

medium cast between the adjacent segments and enveloping that portion of each girder member which lies therebetween and means whereby said girder members may be removably mounted at their opposite ends on a rotatable support.

2. A segmental grinding wheel comprising a multiplicity of abrasive segments arranged independently of any rotatable support to form an annulus, each pair of adjacent segments having opposed reentrant grooves therebetween forming locking shoulders, a plurality of girders located between adjacent segments and interlocking with the opposed shoulders, a cementitious filler in said grooves which envelops the girders and secures each segment rigidly in position, and thereby forms a unitary wheel structure and means whereby the girders may be removably fastened to a support and the wheel be mounted thereon.

3. A grinding wheel comprising an annulus of abrasive segments, each having an inner dovetailed portion, a series of clamping girders having opposed heads and supporting portions located between adjacent segments and so positioned that each dovetailed portion is supported by and firmly secured between two adjacent girders, and a cementitious filler between the faces of adjacent abrasive segments and the girders, thereby forming a unitary abrasive annulus with the girders embedded therein which is independent of any rotatable support.

4. A grinding wheel comprising an annulus of abrasive segments, each having an inner dovetailed portion, a series of clamping girders having opposed heads and supporting portions located between adjacent segments and so positioned that each dovetailed portion is supported by and firmly secured between two adjacent girders, a cementitious filler between the faces of adjacent abrasive segments and the girders, thereby forming a unitary abrasive annulus with the girders embedded therein and means whereby said girders may be removably and firmly mounted upon a central hub for rotation of said annulus therewith.

5. A grinding wheel comprising a hub, two plates removably secured thereto, a plurality of peripherally spaced girders removably affixed to said plates, each of said girders having peripherally extending flanges at its base and a radially extending web portion terminating in an enlarged head, a multiplicity of spaced abrasive segments, each of which is mounted between and supported by the flanges on two adjacent girders and has a cuneated portion interlocking with two opposed girder heads, a cementitious filler between the adjacent abrasive segments and the girders forming an integral grinding annulus, and means for removably securing the girders upon the plates.

6. A grinding wheel comprising a rimless supporting center, a plurality of girders having undercut heads rigidly mounted on said center and arranged parallel with the wheel axis, spaced abrasive segments assembled to form a peripheral grinding surface which have dovetailed portions slidable between said heads and are supported solely on said girders, and a cementitious filler between the segments and said heads and between adjacent faces of the segments which secures the latter rigidly in position and forms an integral wheel structure.

7. A grinding wheel comprising two disks spaced at their peripheries and arranged to be mounted centrally on a spindle, a plurality of spaced girders rigidly connecting the disks at their peripheries, each girder having a head arranged parallel with the wheel axis, spaced abrasive segments arranged to form a peripheral grinding surface which have dovetailed portions slidable between said heads and are supported solely on said girders, and a cementitious filler between the segments and said heads and between adjacent faces of the segments which secures the latter rigidly in position and forms an integral wheel structure.

8. A grinding wheel comprising a hub, a plurality of plates secured thereto, a plurality of girders secured to the internal faces of the plates adjacent their peripheries and arranged to form a sectional rim having a plurality of spaced upstanding webs provided with heads, abrasive segments mounted on the rim in spaced relation to form a grinding surface, the segments having reentrant shoulders which interlock with the heads on the webs, and a filler in the interstices which remain between the adjacent faces of the segments and the heads after the parts have been assembled.

9. A grinding wheel comprising a hub, a plurality of plates secured thereto, a plurality of girders secured to the opposed faces of the plates adjacent their peripheries arranged to form a sectional rim and having integral therewith a plurality of spaced upstanding webs, abrasive segments mounted on the rim in spaced relation to form a cylindrical grinding surface, the segments and webs having cooperating interlocking surfaces necessitating the sliding of the segments on the webs in a direction parallel to the axis of rotation in assembling the segments between the webs, and a filler flowed into the interstices remaining between the adjacent faces of the segments and heads after the assembly of the parts.

10. A grinding wheel comprising a hub, a pair of spaced disks secured thereto, a rim composed of a plurality of separate units secured near the peripheries of the disks, each of said units having integral therewith an upstanding web provided with a wedge-

shaped head, abrasive segments mounted on the rim in spaced relation, each segment having a cuneated portion to fit in between a pair of the heads, and a filler in the interstices between the adjacent faces of the segments and the heads which makes an integral wheel structure thereof.

11. In a wheel structure for supporting a plurality of abrasive segments rigidly held together to form a cylindrical grinding surface, a hub, a plurality of arms radiating therefrom, a pair of disks positioned on the hub on opposite sides of the arms and secured thereto, and a plurality of girders mounted between the disks adjacent their peripheries, each girder having a pair of plates one of which is secured to one of the disks and the other one of which is secured to the other disk, a web between the plates to hold the peripheries of the disks from relative movement, a top plate centrally positioned on the web and forming one element of the wheel rim, and an integral web projecting outwardly from the top plate constructed to have interlocking engagement with a pair of adjacent segments.

12. A grinding wheel mount comprising a pair of parallel disks mounted on a hub for rotation, a series of girders rigidly connecting the peripheral portions of the disks, and spaced wedge-shaped heads arranged on the girders to hold abrasive segments therebetween.

13. A grinding wheel comprising a pair of parallel disks mounted on a hub, a series of peripherally spaced transverse girders rigidly connecting the peripheral portions of the disks and providing spaced enlarged heads, a series of separately fashioned abrasive segments having inwardly projecting portions, each head being located between and interlocked with two adjacent segments, and means to secure the segments rigidly in position.

14. A grinding wheel comprising a pair of parallel disks, a series of peripherally spaced girder like heads rigidly fastened to and between said disks adjacent to their peripheries, independently fashioned abrasive segments, each of which has a reduced portion supported by and interlocked between two adjacent heads, and a cementitious filler between the adjacent segments forming an integral grinding wheel structure.

Signed at Worcester, Mass., this 18th day
55 of Dec. 1930.

THURE LARSSON.
